(57) **CLAIM**

What is claimed is the ornamental design for a single cup coffee caddy, as shown and described.

DESCRIPTION

FIG. 1 is a perspective view of a single cup coffee caddy showing our new design;

FIG. 2 is a front view of the single cup coffee caddy of FIG. 1;

FIG. 3 is a rear view of the single cup coffee caddy of FIG. 1;

FIG. 4 is a right side view of the single cup coffee caddy of FIG. 1;

FIG. 5 is a left side view of the single cup coffee caddy of FIG. 1;

FIG. 6 is a top view of the single cup coffee caddy of FIG. 1;

FIG. 7 is a bottom view of the single cup coffee caddy of FIG. 1; and,

FIG. 8 is a perspective view of a single cup coffee caddy showing a second embodiment of our new design. The single cup coffee caddy is shown broken in the middle along the length and width to indicate indeterminate length, with the understanding that the “indeterminate” length and width portion of the caddy not shown forms no part of the claim design. Patentability is based only on those portions of the article that are shown in solid lines.

The components of the display shown in broken lines illustrate portions of the single cup coffee caddy which form no part of the claimed design.
